UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,130,012.

Specification of Letters Patent.

Patented Mar. 2, 1915.

Application filed March 14, 1913. Serial No. 754,222.

To all whom it may concern:

Be it known that I, JOHN F. O'CONNOR, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide a draft rigging having a compression resisting member adapted to afford an easy preliminary movement in the operation of the draft rigging.

In the drawings forming a part of this 20 specification Figure 1 is a side elevation partly in vertical longitudinal section on line 1—1 of Fig. 2 of a draft rigging for railway cars embodying my invention. Fig. 2 is a plan view partly in horizontal section on line 2—2 of Fig. 1 showing the parts in normal position. Fig. 3 is a plan view partly in horizontal section showing the position of parts in pulling movement of the draft rigging with the preliminary springs 25 fully compressed, and the compression resisting member within the friction shell in normal position. Fig. 4 is a plan view partly in horizontal section showing the position of the parts of the draft rigging under full compression in pulling movement. Fig. 5 is a perspective view of the rear end 30 of the friction shell. Fig. 6 is a perspective view of one of the preliminary springs.

In the drawings 7, 7 represent draft members or parts of the car frame to which the draft rigging is applied, 8 the end sill, 9 the buffer block, 10 the draw bar carry iron, 11 the tie plate, the same being secured by suitable means, preferably the bolts 12, 12, 40 to the draft members 7, 13, 13 the front stop members having the front stop shoulders 14, 14, and the front limiting stop shoulders 15, 15, 16, 16 the rear stop members having the rear stop shoulders 17, 17, 18 45 to the draw bar, 19 the draft yoke comprising the U-shaped yoke strap 20 and the hollow yoke head 21 secured to the free ends thereof, provided with the slots 22, through which and the draw bar the coupler key 23

is passed to connect the draw bar to the 55 draft yoke.

Within the transverse opening 24 of the draft yoke 19 is disposed the front fol- lower 25 and the draft gear 26. The draft gear 26 comprises a shell 27, preferably in 60 form of a hollow cylinder or circular in cross section, closed at its rear end by the preferably integral plate 28 and open at its forward end 29, and containing the fric- tion mechanism 30 and the spring mecha- 65 nism 31.

The friction mechanism consists prefer- ably of the friction shoes 32 and a wedge 33 adapted to spread the said shoes and antifriction rollers 34, there being one of 70 said antifriction rollers inclosed between each friction shoe and the wedge. The wedge is forwardly provided with the recess 35 to receive the head 36 of the connecting rod 37, which passes through the wedge and 75 through the rear member 28 of the friction shell, which is provided with the recess 38 to receive the nut 39 of the said connecting rod. The said plate 28 of the shell is out- 80 wardly extended transversely of the shell, 85 and is preferably rectangular in shape, as illustrated in Fig. 5 of the drawings, having in preferable construction the top and bot- tom reinforcing members 40 extended along the surface of the shell and preferably inte- 90 gral therewith, and the lateral reinforcing ribs 41, which are preferably integral with the shell and the said transverse plate 28. The member 28 is provided at either side with an angular flange 42 forming a recess 95 43 at either end of said plate, adapted to receive the ends 44 of the preliminary spring 45. One of said flanges 42 is provided with a slot 46, which is adapted to permit the passage of a preliminary spring there- 100 through in assembling the same in its position at the rear end of the shell.

The preliminary spring 45 in its normal position is curved rearwardly, the forward face 47 thereof in normal position being con- 105 cave, and the rearward face 48 in normal po- sition being convex. The said preliminary spring 45 preferably consists of a plurality of leaf springs of substantially identical form and dimensions, each being curved, 105 having a concave forward face and a convex rearward face, as illustrated in Fig. 6 of the drawings.

The yoke strap 20 of the yoke 19 is provided at its inner rear end with the filler block 49, the front face 50 of which engages the preliminary spring 45 in normal position of the gear, as illustrated in Fig. 2 of the drawings. On forward movement of the draft yoke in the pulling movement of the draft rigging the said yoke through the said filler block flexes the said springs from the 10 curve toward a flat position, and on complete movement of said preliminary spring 45 the same is straightened against the rear face 51 of the member 28, constituting the rear end of the shell 27, as illustrated in Fig. 3 of the 15 drawings. On the continued pulling movement of the draft rigging and consequent continued forward movement of the draft yoke the preliminary spring remains in the same position in reference to the shell 27, 20 and the friction mechanism 30 and spring mechanism 31 within the shell 27 are thereupon compressed. The position of the parts within the shell on full compressing movement is well understood, and is illustrated by Fig. 4 of the drawings. On buffering movement of the draft rigging the friction mechanism and spring mechanism within the 25 shell resist the rearward movement of the

draw bar, and the preliminary spring maintains its normal position.

It will be apparent that the preliminary spring herein described will afford an easy initial movement of the shock absorbing members of the draft rigging, and a consequent easy start of the railroad car to which 30 the same is applied.

I claim:

In a draft rigging for railway cars, in combination, a draft yoke and a draft gear, the draft gear comprising a shell, compression resisting members within the shell, a transverse plate at one end of said shell and a preliminary spring, the said transverse plate being provided with angular flanges forming a recess to receive the ends of the 45 preliminary springs, the preliminary spring comprising a plurality of plates, each having a concave face, the concave faces being turned toward the rear end of the shell and the said plates being in engagement with the 50 draft yoke.

JOHN F. O'CONNOR.
